MAGNET VALVE DEVICE

Donald L. McNeal, Wilkinsburg, Pa., assignor to
The Westinghouse Air Brake Company, Wil-
merding, Pa., a corporation of Pennsylvania

Application April 16, 1938, Serial No. 202,582

5 Claims. (Cl. 137—139)

This invention relates to magnet valve devices and has particular relation to magnet valve devices for controlling fluid at high pressures.

Valve devices operated by electromagnet coils or solenoids and referred to herein as magnet valve devices have certain inherent limitations when employed in the control of fluid at high pressures. If the electromagnet winding or solenoid of the valve device is to be maintained relatively small in size, the magnetic force which may be exerted thereby is correspondingly limited. Where the force of the solenoid is employed to cause movement of a valve in direct opposition to the pressure of the fluid to be controlled, the fluid pressure which the valve may successfully control is correspondingly limited. On the other hand, if the electromagnet winding or solenoid of the valve is designed to carry relatively high electrical current in order to produce high magnetic forces, then the electrical power consumed to operate the valve is objectionably high. Furthermore, electromagnet windings or solenoids capable of producing high magnetic forces are necessarily large and cumbersome and where a relatively small valve unit is desired, such electromagnet windings or solenoids cannot be employed.

It is accordingly an object of my invention to provide a magnet valve device of relatively small size for controlling fluid at exceptionally high pressures with a minimum of electrical power consumption for operating the valve device.

Another object of my invention is to provide magnet valve devices, of the type indicated in the foregoing object, adapted to operate singly or in pairs in the control of fluid under pressure.

The above objects, and other objects of my invention which will be made apparent hereinafter, are obtained by means of illustrative embodiments of my invention subsequently to be described and shown in the accompanying drawing, wherein:

Figs. 1, 2 and 3 are vertical sectional views, showing respectively three different types of magnet valves embodying my invention.

Figs. 4, 5 and 6 are diagrammatic views, showing the manner in which the several magnet valve devices illustrated in Figs. 1, 2 and 3 may be employed, respectively, and

Fig. 7 is a fragmental sectional view, showing a modified construction for any of the magnet valves shown in Figs. 1, 2 and 3.

Referring to Fig. 1 a magnet valve device 10 is shown comprising a sectionalized tubular casing 55 having a so-called magnet section 11, an inter-

mediate or piston section 12, and a lower or main valve section 13, suitably secured together by means not shown.

Contained in a chamber 14 in the magnet section 11, which is constantly open to atmosphere through a port 15, is an electromagnet winding or solenoid 16 suitably fixed in insulated relation to the casing and effective when energized to actuate a plunger 17 downwardly.

Formed in the casing section 12 is a bore 18 in which a piston 19 operates, the piston having a hollow stem 21 which extends through a passage or bore 22 of reduced diameter into a chamber 23 formed in the casing section 13. Removably secured to the end of the piston stem 21 in the chamber 23, as by being screwed thereon, is a disk valve 25 hereinafter referred to as the main supply valve, which may be provided with an annular gasket 26 on one face thereof adapted and arranged to engage in seated relation on an annular rib seat 27 formed on the casing section 13 at the lower end of bore 22.

Fluid under pressure is supplied to the chamber 23 through an inlet pipe 28 and, when the main supply valve 25 is unseated from the rib 25 seat 27, fluid under pressure flows into the passage 22 to which an outlet pipe 29 is connected.

Two oppositely seating pilot valves 31 and 32, illustrated as of the poppet type having fluted stems 33 and 34 respectively are provided, the valve 31 being contained in the chamber 14 of the casing section 11 and seating downwardly on its associated valve seat 35 formed on the casing section 11, and the valve 32 being contained in the chamber 23 of the casing section 13 and seating upwardly on an associated valve seat 36 formed at the lower end of the stem 21 of the piston 19. A bore or passage 38 extends longitudinally through the piston 19 and its stem 21, and the fluted stem 34 of the valve 32 extends upwardly through the bore 38 into a chamber 39 formed at the upper side of the piston 19. A coil spring 41, interposed between the valve 32 and a cover plate 42 which closes the chamber 23 of the casing section 13, yieldingly urges the valve 32 upwardly into seated relation on its associated seat 36.

The fluted stem 33 of the valve 31 operates slidably in a bore 45 connecting the chamber 14 in the casing section 11 to the chamber 38 above the piston 19 and engages the end of the stem 34 of the valve 32.

The length of the fluted stems 33 and 34 of the valves 31 and 32 is such as to cause the valves 31 and 32 to seat oppositely. That is, when the

valve 32 is seated, the valve 31 is unseated; and when the valve 31 is seated on its associated seat 38, the valve 32 is unseated.

The lower end of the plunger 17 engages the upper face of the valve 31 in the chamber 14 and, when shifted downwardly in response to energization of the solenoid or electromagnet winding 16, shifts the valves 31 and 32 simultaneously to seated and unseated positions, respectively. When the solenoid 16 is deenergized, the spring 41 returns the valves 31 and 32 to unseated and seated positions, respectively.

In operation, with the solenoid 16 deenergized, the spring 41 seats the pilot valve 32 on the main supply valve 25 and unseats the pilot valve 31, thereby connecting the chamber 39 above the piston 19 through the bore 48 to chamber 14 and thence to atmosphere through the port 15. Accordingly, with fluid under pressure supplied into the inlet pipe 28, the main valve 25 is seated and maintained seated by the pressure of the fluid in the chamber 23 as well as by the force of the spring 41.

When the solenoid 16 is energized and the pilot valves 31 and 32 shifted downwardly to seated and unseated positions respectively, fluid under pressure supplied into the chamber 23 flows past the unseated pilot valve 32 through the bore 38 in the stem 21 of the piston 19 to the chamber 39 above the piston 19. Since the pilot valve 31 is seated, the pressure of the fluid is confined to the chamber 39 and exerts a force urging the piston 19 downwardly into engagement with a stop shoulder 30 on casing section 12 to unseat the main valve 25. When the main valve 25 is unseated, fluid under pressure flows from the inlet pipe 28 through the chamber 23 into the passage 22 and out through the outlet pipe 29.

The chamber 48 at the lower face of the piston 19 is open to the passage 22 through a port 24 in a guide bushing 26 for the piston stem 21. Thus, assuming that the solenoid 16 is maintained energized, the opposing fluid pressure forces on the piston 19 are ultimately balanced. The piston 19 thus remains in engagement with the stop shoulder 30 and the main supply valve 25 remains unseated.

When the solenoid 16 is deenergized and the magnetic force urging the plunger 17 downwardly is accordingly relieved, the spring 41 becomes effective to shift the valves 31 and 32 upwardly into unseated and seated positions, respectively. It will be observed that the distance which the main supply valve 25 is unseated is less than the distance which the pilot valve 31 moves to seat on its seat 38, and thus with the main valve 25 unseated, seating of the pilot valve 32 results in the unseating of pilot valve 31. Fluid under pressure in the chamber 39 above the piston 19 is thus rapidly reduced to atmosphere past the unseated pilot valve 31, through the chamber 14 and exhaust port 15 and the pressure of the fluid acting in chamber 48 on the lower face of the piston immediately shifts the piston 19 upwardly and causes the main supply valve 25 to return to seated relation on its seat 27 to close off the connection between the inlet pipe 28 and the outlet pipe 29.

If it is desired to control both the supply and the release of fluid under pressure from a reservoir, pipe or other receiver, two of the magnet valve devices 10 may be employed in combination, as illustrated in Fig. 4. As indicated in Fig. 4, the solenoids of the two magnet valve devices 10 are energized by current supplied from a source,

such as a battery 50, under the control of corresponding switch devices 51. One of the magnet valve devices controls the supply of fluid under pressure from a source, such as a reservoir 52, to a control pipe 53 while the other magnet valve device controls the release of fluid under pressure from the control pipe 53 to atmosphere. Thus, with the switch 51 for the supply magnet valve open and that for the release magnet valve closed, as shown, control pipe 53 is vented to atmosphere. In order to charge the control pipe with fluid under pressure the switch for the release magnet valve is opened and that for the supply magnet is closed.

In order to accurately obtain desired pressure in the control pipe 53, a choke element 55 having a restricted passage 56 therein may be provided, as shown in Fig. 7, to restrict the rate of flow of fluid under pressure from the inlet pipe 28 into the chamber 23 of the magnet valve device. The rate of variation of pressure in the control pipe 53 shown in Fig. 4 is thus restricted so as to enable the control of the magnet valve devices 10 by the switches 51 to establish a desired pressure in the control pipe 53.

It will be apparent that the magnet valve devices 10 are adapted to control fluid at relatively high pressures while maintaining the size of the solenoid 16 relatively small, because the solenoid need be only of sufficient size to exert a force sufficient to overcome the combined force of spring 41 and the force of the fluid pressure in the chamber 23 acting on the face of the pilot valve 42. Since the actual size of the pilot valve 32 may correspond to that shown in Fig. 1 or be even smaller, it will be seen that a relatively small size solenoid is required, notwithstanding the high pressures of fluid which may be controlled by the main valve 25.

Referring to Fig. 2, a magnet valve device 60 of modified form to that of the magnet valve device 10 is shown. Magnet valve device 60 differs from the magnet valve device 10 essentially in the arrangement of the valve parts in such manner that the solenoid corresponding to the solenoid 16 must be energized in order to cause seating of the main supply valve 25 as distinguished from the magnet valve device 10 where the solenoid must be deenergized to cause seating of the valve 25.

The casing of the magnet valve device 60 is tubular in shape and comprises an upper section 61 and a lower section 62 suitably secured together as by screws not shown and having end covers 63 and 64 at opposite ends thereof secured to the sections 61 and 62 respectively.

Formed in the casing section 61 is a chamber 66 having an inlet pipe 28 connected thereto and containing a solenoid (not shown), similar to the solenoid 16 of the magnet valve 10, and an associated plunger 17. Also formed in the casing section 61 is a chamber 68 to which an outlet pipe 29 is connected, the two chambers 66 and 68 being separated by a wall 69 having a bore or passage 71 therein connecting the two chambers. Formed on the wall 69 surrounding the passage 71 and within the chamber 66 is an annular rib 72 on which the main supply valve 25 is adapted to seat to close communication between the chambers 66 and 68.

The lower casing section 62 has formed therein a bore 73 in which the piston 19 for operating the main valve 25 is contained, the stem 21 of the piston being guided slidably in a bushing 74, fixed in the lower wall 75 of the casing section 61, and

extending through the chamber 68 and passage 71 to the chamber 66 where the main supply valve 25 is secured thereto.

The wall 75 of the casing section 61 contains a port 76 which connects the chamber 68 with a chamber 77 at the upper side of the piston 19 within the casing section 62.

A wall 79 of the casing section 62 is located between the piston 19 and the end cover 64 so as to form a chamber 81 between the lower face of the piston 19 and the wall 79, and a chamber 82 between the wall 79 and the end cover 64. The chamber 81 is constantly connected to the chamber 82 through a restricted port 83 in the wall 79 and the chamber 82 is constantly open to atmosphere through an exhaust port 84.

A pilot valve 85 of the poppet type is contained in the chamber 66 and arranged so as to be shifted downwardly by the plunger 17 into seated relation on an associated valve seat 86, formed on the end of the piston stem 21 within the chamber 66. The pilot valve 85 has a fluted stem 87 which is slidably guided in a longitudinal bore 88 in the stem 21 of the piston 19. A stem 89 having a fluted upper portion and a smooth lower portion is contained in the bore 88 in the piston stem 21 and extends downwardly through a circular opening 91 in the wall 79 into the chamber 82. The smooth portion of the stem 89 fits closely in the opening 91 to prevent appreciable leakage of fluid under pressure from the chamber 81 to the chamber 82 along the stem 89.

Fixed to the lower end of the stem 89 within the chamber 82 is a collar or flange 92. A coil spring 93, interposed between the collar 92 and end cover 64, yieldingly urges the stem 89 upwardly until stopped by the engagement of the collar 92 with the wall 79. The upper end of the stem 89 engages the lower end of the fluted stem 87 of the pilot valve 85 within the longitudinal bore 88 of the piston stem 21 and, when the solenoid associated with the plunger 17 is de-energized, the spring 93 urges the stem 89 upwardly to effect unseating of the pilot valve 85 from its valve seat 86. When the solenoid of the magnet valve 60 is energized, the force of the plunger 17 on the pilot valve 85 shifts it downwardly into seated position against the yielding resistance of the spring 93.

In operation, when the solenoid of the magnet valve 60 is energized and the plunger 17 actuated downwardly to seat the pilot valve 85, the supply of fluid under pressure from the inlet pipe 28 and chamber 66 through the longitudinal passage 88 of the piston stem 21 to the chamber 81 beneath the piston 19 is cut off and, accordingly, the pressure in chamber 81 is reduced to atmospheric pressure by flow of the fluid in the chamber through the restricted port 83, chamber 82 and exhaust port 84. The piston 19 and main valve 25 accordingly move downwardly until the main valve 25 seats on the annular rib seat 72 at which time the pressure of the fluid in the chamber 66 as well as the magnetic force on plunger 17 is effective to maintain the valve 25 seated. With the main valve 25 seated, the connection between the inlet pipe 28 and the outlet pipe 29 is closed.

When the solenoid for the magnet valve 60 is de-energized, the spring 93 unseats the pilot valve 85 from its associated valve seat 86 and fluid under pressure from the chamber 66 flows past the unseated valve 85 through the longitudinal passage 88 in piston stem 21 to the chamber 81 beneath the piston 19. The flow area of re-

stricted port 83 is relatively small compared to the flow area through the bore 88 in the piston stem 21 and, consequently, pressure is rapidly built-up in the chamber 81. When the upward force on the piston 19 exerted by the fluid pressure in chamber 81 is greater than the downward fluid pressure force on the main valve 25, the piston 19 is shifted upwardly to effect unseating of the main valve 25. The engagement of the upper face of the piston 19 with the wall 75 limits the unseating movement of the main supply valve 25 to an amount which is insufficient to reseat the pilot valve 85 and thus the communication from the chamber 66 to the chamber 81 remains open past the pilot valve 85 when the main valve 25 is unseated.

With the main supply valve 25 unseated, fluid under pressure is supplied from the inlet pipe 28 and chamber 66 through the passage 71 to the chamber 68 and outlet pipe 29, the pressure of the fluid in the chamber 68 being effective, through the port 76, in chamber 77 on the upper face of the piston 19.

Since fluid under pressure is exhausted through port 83 from chamber 81 at a restricted rate, the pressure built up in chamber 81 is maintained and thus fluid under pressure continues to be supplied past the unseated main supply valve 25 until the solenoid is energized or until the pressure in the outlet pipe 29 equalizes with that in the inlet pipe 28. When the solenoid is energized and the plunger 17 actuated downwardly to reseat the pilot valve 85 on its seat 86, the connection between the chamber 66 and the chamber 81 is closed and consequently the fluid under pressure in the chamber 81 is rapidly vented to atmosphere through the restricted port 83, chamber 82 and exhaust port 84. It should be understood that although the port 83 is a restricted port, the volume of the chamber 81 is relatively small and accordingly when the pilot valve 85 is reseated, the chamber 81 is almost instantly reduced to atmospheric pressure.

Upon the reduction of the pressure in the chamber 81, the pressure of the fluid in chamber 71 above the piston 19 is effective to urge the piston downwardly and thereby reseat the main supply valve 25 to close the connection between the inlet pipe 28 and outlet pipe 29.

Referring to Fig. 5, the manner in which a pair of magnet valve devices 60 may be employed to control the supply and the release of fluid under pressure from a control pipe is indicated. As in the arrangement shown in Fig. 4 for magnet valve 60, the solenoids of the magnet valve 60 are arranged to be energized by current supplied from a battery 50 under the control of corresponding switches 51. As shown, the switch 51 for the magnet valve 60 controlling the supply of fluid under pressure from the reservoir 52 to the control pipe 53 is closed so that the solenoid is energized and the supply of fluid under pressure from the reservoir to the pipe 53 cut off. At the same time, the switch 51 for the second magnet valve 60 is in open position so that the solenoid of the second magnet valve is deenergized and thereby conditioned to release fluid under pressure from the pipe 53 to atmosphere.

If it is desired to establish a certain pressure in pipe 53, switch 51 for the release magnet valve 70 is first closed to cut off the release communication for the pipe 53 and then the switch 51 for the supply magnet valve is opened, thereby effecting operation of the supply magnet valve to cause fluid under pressure to flow from the res-

ervoir 52 to the pipe 53. When the desired pressure is established in the pipe 53, switch 51 for the supply magnet valve is reclosed and the further supply to the pipe 53 cut off.

- 5 As in the case of magnet valve 10, the magnet valves 60 of Fig. 5 may be provided with a choke element 55 in the passage between the inlet pipe 28 and the chamber 66 to restrict supply of fluid under pressure past the main valve 25 sufficiently 10 to enable graduated control of the pressure in the pipe 53.

15 Referring to Fig. 3, a magnet valve device 100 is shown which embodies the fundamental principles of my invention and which differs from the magnet valves 10 and 60 in performing both supply and release functions in a single unit instead of requiring two units as is the case with the magnet valves 10 and 60. The magnet valve 100 is suited particularly to those applications in 20 which either full pressure or atmospheric pressure is required, there being no need for graduated or intermediate pressure.

25 The casing of the magnet valve 100 is tubular in shape and comprises an upper magnet section 101, a lower valve section 102, and an intermediate section 103, together with end covers 104 and 105 for the sections 101 and 102, respectively.

30 Formed in the magnet section 101 is a chamber 107 in which is contained a solenoid, corresponding to solenoid 16, for actuating a plunger 17.

35 The intermediate casing section 103 has formed therein a chamber 108 which is constantly open to atmosphere through an exhaust port 109.

40 The valve section 102 of the casing has formed in the lower end thereof a chamber 111 which is closed by the end cover 105, to which chamber the inlet pipe 28 is connected. Another chamber 112, to which the outlet pipe 29 is connected, 45 is formed in the casing section 102 and is open to the chamber 111 through a bore 113. Opening out of the opposite side of the chamber 112 in axial relation to the bore 113 is a bore 115 which opens into a bore 116 of larger diameter than the bore 115.

45 A piston valve 118 operates in the bore 116 and has a portion of reduced diameter fluted longitudinally for a purpose hereinafter made apparent and guided in the bore 115. The piston valve 50 55 is formed as a poppet valve so that when moved downwardly it seats on a conical valve seat 119 formed between the two bores 116 and 115.

55 The piston valve 118 is normally unseated upwardly from the valve seat 119 and a plurality of ports 121 at spaced intervals around the casing section 102 open into the bore 116 beneath the piston. It will thus be apparent that when the piston valve 118 is raised from the valve seat 119, 60 the chamber 112 is connected to atmosphere through the ports 121 and the longitudinal grooves on the fluted reduced portion of the piston.

65 The piston valve 118 has a stem 123 which extends downwardly through the chamber 112 and passage 113 into the chamber 111, and a main supply valve 25, corresponding to the main supply valve 25 of the magnet valve devices 10 and 60, is removably secured thereon within the chamber 70 75 111. A fluted collar or flange 125 formed on the stem 123 is guided slidably in the bore 113 in the casing.

75 Formed on the lower end of the stem 123 is a valve seat 126 on which a pilot valve 127 of the poppet type is adapted to seat. A coil spring

128 interposed between the pilot valve 127 and the end cover 105 yieldingly urges the pilot valve 127 into seated relation on the valve seat 126. The pilot valve 127 has a fluted stem 129 which extends upwardly through and is slidably guided 5 in a longitudinal bore 131 extending through the piston valve 118 and its stem 123, the end of the fluted stem 129 projecting beyond the upper face of the piston valve 118 into a chamber 132 formed between the upper face of the piston valve and a wall 133 of the intermediate casing section 103. 10

15 Contained in the chamber 108 of the casing section 103 is a poppet valve 134 which has a fluted stem 135 that extends through a circular opening 136 in the wall 133 into the chamber 132 and engages the upper end of the fluted stem 129 of the pilot valve 127. Formed on the wall 133 in surrounding relation to the opening 136 is a valve seat 137 on which the valve 134 seats when shifted downwardly. The fluted stems 129 and 135 of the valve 127 and 134 are of such lengths as to cause the valves 127 and 134 to seat oppositely. That is, when the pilot valve 127 is seated the valve 134 is unseated, and vice versa. 20

25 Formed in a wall 138 of the casing section 101 is a circular opening 139 which connects the chamber 107 to the chamber 108. A flanged disk-like stop member 141 is slidably movable in the opening 139, and a coil spring 142 interposed between the valve 134 and stop member 141 is 30 effective to urge the stop member 141 upwardly until the flange on the stop member engages the wall 138. The spring 142 is of such length or strength as not to prevent unseating of the valve 134 by the spring 128. 35

35 The plunger 17, actuated by the solenoid, is arranged to engage the upper face of the stop member 141 so that when the plunger 17 is urged downwardly it acts to shift the valve 134 downwardly through a resilient connection formed by 40 the spring 142.

45 The spring 142 and stop 141 are provided in cases where over-travel of the plunger 17 after the valve 134 seats is desired. If such over-travel is not required, the spring 142 and stop 141 may be omitted and the plunger 17 may then directly engage the valve 134.

50 A simple application of the magnet valve 100 is indicated in Fig. 6, wherein the solenoid of the magnet valve is energized by current supplied from a battery 50 under the control of a switch 51, the inlet pipe 28 being connected to a source of fluid under pressure, such as a reservoir 52; and the outlet pipe 29 being connected to a control pipe 53. 55

55 In operation, with the solenoid of the magnet valve device 100 deenergized, the pilot valves 127 and 134 are seated and unseated, respectively, and the piston valve 118 and main supply valve 25 are raised to unseated and seated positions, 60 respectively. Accordingly, the supply of fluid under pressure from the reservoir 52 is cut off by the main supply valve 25 and the control pipe 53 and outlet pipe 29 leading thereto are vented to atmosphere through the exhaust ports 121. 65

70 When the solenoid of the magnet valve 100 is energized, the pilot valves 127 and 134 are shifted to unseated and seated positions, respectively. With the pilot valve 134 seated, the connection between the chamber 132 and the atmospheric port 109 is cut off and with the pilot valve 127 unseated, fluid under pressure is supplied to the chamber 132 from the reservoir 52. The area of the piston valve 118 subject to the pressure of the fluid in chamber 132 is larger than the area 75

of the main supply valve 25 subject to the pressure of the fluid in the chamber 111 and, consequently, when the pressure of the fluid in the chamber 132 increases sufficiently the piston valve 118 is shifted downwardly into seated relation on its valve seat 119 and simultaneously unseats the main supply valve 25. With the piston valve 118 seated on the valve seat 119, the exhaust communication from the outlet pipe 29 to atmosphere through the exhaust ports 121 is closed and with the main supply valve 25 unseated, fluid under pressure is supplied thereto through the passage 113 and chamber 112 to the outlet pipe 29 and control pipe 53.

15 As previously explained, the magnet valve 100 is intended primarily as an "on-and-off" device and, consequently, the solenoid is maintained energized until the full or maximum pressure is attained in the control pipe 53. The area of the piston valve 118 subject to the pressure of the fluid in chamber 132 is larger than the area of the piston valve subject to the pressure of the fluid in the chamber 112 and, consequently, the piston valve 118 is maintained seated on the 20 valve seat 119 by the differential of the fluid pressure forces in the chambers 132 and 112.

When the solenoid of the magnet valve 100 is subsequently deenergized, the pilot valves 127 and 134 are shifted upwardly to seated and unseated 25 positions, respectively. It will be observed that the downward movement of the piston valve 118 into seated relation on its valve seat 119 is less than the amount of movement of the pilot valves 127 and 134 relative to their associated valve seats, and consequently when the pilot valve 127 is shifted upwardly into seated relation on the stem 123 of the piston valve 118 while the piston valve 118 seated on its valve seat 119, the pilot valve 134 is unseated.

40 When the pilot valve 134 is unseated, the chamber 132 is vented to atmosphere by way of chamber 108 and exhaust port 109 and, consequently, the pressure of the fluid in the chamber 112 becomes effective to shift the piston valve 118 upwardly away from its valve seat 119 and thereby returns the main supply valve 25 to seated position. Thus, communication from the supply reservoir 52 to the outlet pipe 29 is cut off and the exhaust communication from the outlet pipe 29 45 to atmosphere through the exhaust ports 121 is established. Obviously, once the main supply valve 25 is seated, it is thereafter maintained seated, until the solenoid is energized, by the force of the fluid pressure acting in chamber 111 50 assisted by the force of the spring 128, which force is greater than the combined weight of the piston valve 118, stem 123 and the valve 25.

Summary

60 Summarizing, it will be seen that I have disclosed a plurality of types of magnet valve devices embodying my invention, each of the types shown being provided with a relatively small sized solenoid consuming a relatively small amount of power but adapted to effect operation of the magnet valve devices to handle fluid at relatively high pressure.

It will be understood that while I have shown only several specific embodiments of my invention, various omissions, additions or modifications may be made in the embodiments shown without departing from the spirit of my invention. It is accordingly not my intention to limit the scope of my invention except as it is necessarily limited by the scope of the prior art.

Having now described my invention, what I claim as new and desire to secure by Letters Patent, is:

1. A magnet valve device comprising a casing having a chamber constantly connected to a source of fluid pressure, a second chamber to which an outlet passage is connected, a valve controlling communication between said chambers adapted to be maintained seated by the pressure of the fluid in the first said chamber, a third chamber, a movable abutment subject on one side to the fluid pressure in the said second chamber and on the opposite side to the pressure of the fluid in said third chamber, valve means for controlling the supply of fluid under pressure from the first said chamber to the said third chamber to cause said movable abutment to operate to unseat the said valve and for controlling the release of fluid under pressure from the said third chamber for causing said abutment to operate to seat said valve in response to the pressure of the fluid in said second chamber, and a solenoid for effecting operation of said valve means.

2. A magnet valve device comprising a casing having a chamber constantly connected to a source of fluid pressure, a second chamber to which an outlet passage is connected, a valve controlling communication between the first and second chambers, a third chamber, a movable abutment subject on one side to the pressure of the fluid in the said second chamber and on the opposite side to the pressure in said third chamber, said movable abutment having a passage therein through which fluid under pressure may be supplied from the first said chamber to the said third chamber, a pair of oppositely seating pilot valves one of which controls the supply of fluid under pressure through the said passage from the first said chamber to the said third chamber and the other of which controls the release of fluid under pressure from the said third chamber, and a solenoid effective when energized to operate the said pilot valves so as to cause an increase in pressure in the said third chamber and consequent shifting of the movable abutment to effect unseating of the said valve and effective when deenergized to operate the said pilot valves to effect the release of fluid under pressure from the said third chamber whereby the said movable abutment is actuated by the pressure of the fluid in the said second chamber to effect seating of the said valve.

3. A magnet valve device comprising a casing having a first chamber constantly connected to a source of fluid pressure, a second chamber to which an outlet passage is constantly connected, a pair of oppositely seating main valves one of which is contained in the said first chamber and controls communication between the first and second chambers and the other of which controls communication between the second chamber and atmosphere, said one main valve being subject to the pressure of the fluid in the said first chamber and normally maintained thereby in seated position to close communication between the said first and second chambers and to cause unseating of the said other main valve to open communication from the second chamber to atmosphere, fluid pressure responsive means for operating said main valves, pilot valve means for controlling the supply and the release of fluid under pressure to control the pressure of fluid acting on the fluid pressure responsive means,

and a solenoid for effecting operation of said pilot valve means.

4. A magnet valve device comprising a casing having a first chamber constantly connected to a source of fluid pressure, a second chamber to which an outlet passage is connected, a pair of oppositely seating main valves, one of which is contained in the said first chamber and maintained in seated position to close communication between the said first and second chambers by the pressure of the fluid in said first chamber, the other of said main valves being simultaneously unseated to establish an exhaust communication from said second chamber to atmosphere, a third chamber, a movable abutment for operating said main valves subject on one side over a certain area to the pressure of fluid in said third chamber and subject on the opposite side over a lesser area to the pressure of fluid in the said second chamber, said movable abutment being effective when subject to the pressure of fluid in said third chamber to operate the said one and the other of the main valves to unseated and seated positions respectively and effective to maintain said main valves in such position by the differential of the fluid pressure forces acting on opposite sides thereof notwithstanding equalization of the fluid pressure on opposite sides thereof, pilot valve means controlling the supply and the release of fluid under pressure to and from

said third chamber, and a solenoid for effecting operation of said pilot valve means.

5. A magnet valve device comprising a casing having a chamber connected to a source of fluid under pressure, a second chamber to which an outlet passage is connected, a third chamber, a movable abutment carrying two oppositely seating valves one of which is contained in the said first chamber to control communication between the first chamber and the second chamber and the other of which is arranged to control communication between the second chamber and atmosphere, said movable abutment having a passage therein through which fluid under pressure may flow from the said first chamber to the said third chamber, a first pilot valve arranged to control communication through the said passage to admit fluid under pressure from the first chamber to the third chamber, a second pilot valve arranged to release fluid under pressure from the said third chamber, said movable abutment being shifted in a direction to unseat said one valve and seat the other of said valves upon the supply of fluid under pressure to the said third chamber and shifted in the opposite direction to seat said one valve and unseat the other of said valves upon the release of fluid under pressure from said third chamber, and a solenoid for effecting operation of said pilot valves to control the pressure in the said third chamber. 30
